Attorney

UNITED STATES PATENT OFFICE.

STEPHEN A. GLYNN, OF ANTIGO, WISCONSIN.

BUTTON.

1,340,390.

Specification of Letters Patent.

Patented May 18, 1920.

Application filed November 20, 1919. Serial No. 339,515.

To all whom it may concern:

Be it known that I, STEPHEN A. GLYNN, a citizen of the United States, residing at Antigo, in the State of Wisconsin, have invented certain new and useful Improvements in Buttons; and I do hereby declare that the following is a full, clear, and exact description of the invention, such as will enable others skilled in the art to which it appertains to make and use the same.

The present invention has relation to improvements in buttons and more particularly appertains to the detachable type of garment fasteners.

The principal object of the invention is to provide a button of sectional construction, adapted for detachable connection to a garment and wherein the button elements have interlocking engagement one with the other.

A further object is to provide a device of the character set forth that is capable of adjustment, to separate the interlocking parts for detachment from the garment.

With the above and other objects in view which will hereinafter appear as the description continues, the invention consists of the novel features of construction, combination and formation of parts as will be hereinafter more fully described and particularly pointed out in the appended claim.

In the accompanying drawings has been shown a simple and preferred form of the invention, it being, however, understood that no limitation is necessarily made to the precise structural details herein exhibited, but the right is hereby reserved to any changes, alterations or modifications to which recourse may be had that come within the scope of the claim without departing from the spirit of the invention or sacrificing the efficiency of the same.

The invention has been illustrated in its preferred and modified embodiments in the accompanied drawings, wherein,

Figure 1 is an elevational view of the preferred form of button;

Fig. 2 is a bottom plan view of the same;

Fig. 3 is a disassembled elevational view;

Fig. 4 is a plan elevation of the base element of the button;

Fig. 5 is a plan elevation of the spring member with the base shown diagrammatically;

Fig. 6 is a transverse sectional view of the

base element and spring, illustrating a portion of the top shank in elevation and in position prior to the locking movement;

Fig. 7 is a similar view with the shank in locked position in the base.

In carrying out the present invention, reference being had to the drawing in detail, there is provided a button comprising a hollow annular base casing and a solid head section. The base casing is of sectional construction, being formed of upper and lower plates 10 and 11. In the formation of the upper plate 10, the metal is struck in such manner as to provide a centrally disposed flat annular portion 12 and the depending walls of said plate 10 extend downwardly in concave-convex continuity whereby the lower peripheral edge 13 of the same will engage the inner surface of the lower plate 11. The lower plate 11 has its outer marginal edge portion 14 bent or lapped over the edge portion 13 of the upper plate and the said elements at this point are held together. The upper plate 10 is provided at its central part with a rectangular opening 15, and the lower plate at its central part is pressed outwardly to form an embellishment 16.

The flat annular portion 12 of the upper plate section 10 is formed with the rectangular opening 15, and likewise the metal at this point is indented or notched at the opposite sides of said opening 15 to form the upwardly projecting ridges 17. These ridges 17 extend at right angles to the said rectangular opening or slot 15 and may with the said opening be made at one operation.

The top section of the improved button comprises the flat annular head 18 and shank 19, the lower end of the latter being formed with a restricted portion 20, which is expanded into a substantially wedge-shaped lug 21, the inwardly tapering chisel edges 22 of which are gradually rounded. The shank 19 immediately above the restricted portion 20, is swelled outwardly as at 23 to approximately the same width in cross section, as at the upper widest part of the wedge shaped lug 21.

When plates 10 and 11 are assembled, a spring plate 24 is disposed within the hollow interior of the plate 10 and has its opposite ends curved downwardly. The edge portions 25 of the plate 24 engage the inner sur-

face of the lower plate 11, while the curved portions of the plate 24 will engage portions of the upper plate at the intersecting point of the inner and outer curves of the wall of the upper casing plate 10, so that a certain degree of resiliency is imparted to the central part of said plate at which point it is formed with a bearing notch 26.

The top section of the button is connected 10 to the casing 10, by adjusting shank 20 in such manner that the wedge lug 21 is in register with the slot 15, then forcing down upon the head 18, thereby seating the lug 21 within the spring plate notch 26, and forcing said plate downwardly. The top section is then turned, at which time the lug is below the annular flat surface 12, and consequently the shoulders 27 of the lug 21 will seat within the notches formed by the ridges 15 17, being upwardly tensioned by the spring 20 plate 24.

It is obvious, that to detach the button sections of this form, it is only necessary to push inwardly upon the top section, revolve 25 the same until the lug 21 is moved into registration with slot 15 of the plate 10 and then lift up and remove the said top section.

Having thus fully described my invention,

what I claim as new and desire to secure by Letters Patent is:

As a new article of manufacture, a separable button comprising upper and lower interlocking sections, said upper section having a head and shank, said shank provided with a restricted portion expanding into a wedge-shaped lug, said lower section comprising upper and lower plates connected together to form a hollow casing, the upper of said plates formed with a raised annular portion having a rectangular opening therein, said annular portion provided with notches extending at right angles to said opening, a spring plate arranged within said hollow casing and having its opposite ends curved downwardly, the end portions of said spring plate engaging the lower casing plate and the curved portions of said spring plate engaging said upper casing plate, said spring plate being indented at its central part for the reception of the said lug and adapted for tensioning said shank lug into notches of the raised annular portion of the said casing.

In witness whereof I have hereunto set my hand.

STEPHEN A. GLYNN.
